UNITED STATES PATENT OFFICE.

RILEY DOTY, OF LEONARDSBURG, OHIO.

VALVE FOR STEAM-ENGINES.

SPECIFICATION forming part of Letters Patent No. 283,978, dated August 28, 1883.

Application filed December 27, 1882. (No model.)

To all whom it may concern:

Be it known that I, RILEY DOTY, of Leonardsburg, in the county of Delaware and State of Ohio, have invented a new and useful Improvement in Valves for Steam-Engines, of which the following is a full, clear, and exact description.

My invention relates to improvements in that class of valves for steam-engines in which one valve for the steam and another valve for the exhaust is used; and it consists in the peculiar construction and arrangement of parts, as hereinafter fully described, and pointed out in the claim.

Reference is to be had to the accompanying drawings, forming part of this specification, in which similar letters of reference indicate corresponding parts in all the figures.

Figure 1 is a plan view of a steam-chest and valves of my improved arrangement. Fig. 2 is a sectional plan view of the valve-seat. Fig. 3 is a longitudinal section on line $x x$; Fig. 1. Fig. 4 is a longitudinal section on line $y y$, Fig. 1. Fig. 5 is a transverse section on line $z z$, Fig. 3.

A is the steam-chamber and valve-chest, which is made of a width for receiving two valves, B B' . The valve-seat is formed with two parts, a a , that connect with steam-passages leading to the opposite ends of the cylinder, and the steam-valve B' , working upon the ports a , is made simply as a plain flat valve, connected to a stem, b , for reciprocation.

c c are the exhaust-ports in the seat, connecting beneath the face of the seat with the steam-passages d d .

c' is the main exhaust-port between the two ports c c . The exhaust-valve B , working over the ports c c' , is formed as a bridge-valve, so that when reciprocated by its stem b' the ports c are connected alternately with the middle port, c' .

The two valves are to be operated by separate eccentrics, and it will be seen that they can be readily and independently adjusted so that the valve B' will cut off the steam from the cylinder at any point in the stroke of the piston and the valve B will allow the exhaust at any point, and the exhaust-port may be kept open until the piston-head has reached the end of the stroke, whereby the resistance offered to the piston in returning the same when the exhaust is closed is avoided.

Having thus described my invention, what I claim as new, and desire to secure by Letters Patent, is—

In a steam-engine, the combination, with the steam-chest A , provided with the steam-ports a a , the exhaust-ports c c' , and the passages d , of plain steam-valve B' and the bridge exhaust-valve B , substantially as herein shown and described, whereby provision is made for cutting off the steam at any point in the stroke of the piston and keeping the exhaust open until the piston has returned to the end of the cylinder, as set forth.

RILEY DOTY.
